PROCESS OF MAKING SOAP

Benjamin Clayton, Houston, Tex., assigner to
Refining, Inc., Reno, Nev., a corporation of
Nevada

Application December 26, 1946, Serial No. 371,811

7 Claims. (Cl. 269—418)

The present invention relates to a process of refining animal and vegetable oils and to a process of making soap, the latter utilizing the soap stock obtained from the oil refining process.

In certain glyceride oil refining processes a considerable excess of alkali over that required to neutralize the free fatty acids and to remove other impurities, is employed. When the neutralized fatty acids, together with the excess alkali, water and other impurities are separated from the refined oil, the separated material is found to contain a large excess of alkali. For example, in my prior Patent 2,190,594, I have described a process for refining glyceride oils in which soda ash in the proportion of from three to twelve times the amount required to neutralize the free fatty acids may be employed. The separated soap stock from such a process contains a large excess of alkali. The present invention contemplates the use of this soap stock with its excess alkali as a saponifying agent for the production of soap. The alkali-soap stock mixture may be added to a quantity of either free fatty acids, glycerides, or other saponifiable material and the same run through a soap making process. In this manner it is possible to make use of a low cost material as the saponifying agent.

Crude glyceride oils consist chiefly of fatty acid glycerides and contain minor proportions of impurities such as fatty acids, gums, phosphatides, coloring matter and the like. In the preparation of edible oils it is usually desired to remove the major proportion of these impurities. However this may be done in a number of ways. For example, the crude oil containing all the impurities may be directly subjected to an alkali refining operation which removes the major proportion of all these impurities. It will be apparent that the soap stock or soots resulting from such a refining operation would contain in addition to the soap resulting from the neutralization of the free fatty acids, the gums, phosphatides, coloring matter and other impurities. This soap stock may be employed in the present process where a high quality soap is not the primary consideration. It will be apparent that soap made from this soap stock by ordinary batch processes will contain various quantities of the impurities present in the soap stock. It is extremely difficult to remove certain of such impurities from a soap made from the soap stock.

In refining operations it is sometimes desirable to subject the oil to a degumming operation prior to the alkali refining. Such an operation may consist of mixing the crude oil with various quan-

tities of water or electrolytes such as weak solutions of boric acid and the like, which serve to precipitate the gums and phosphatides following which the precipitated impurities may be separated from the oil. In general solutions of weak acids or alkalies such as alkali metal salts or extremely dilute solutions of strong alkalies or acids are suitable. The separated oil may then be subjected to an alkali refining operation and it will be evident that the soap stock resulting from such a refining operation will be free from many of the impurities encountered in a soap stock resulting from the refining of crude oil. Accordingly when such a relatively pure soap stock is employed as the saponifying agent according to the present invention the final soap resulting will be of a high grade.

In still other refining operations the free fatty acids may be neutralized by means of an alkali and may be separated from the oil, the quantity of alkali employed being intended primarily for the removal of free fatty acids. Such an oil may then be subjected to a second alkali treatment for the removal of color. It will be apparent that the soap stock resulting from such an operation will be relatively free of color impurities. Accordingly, where such a soap stock is employed as the saponifying agent according to the present invention the final soap resulting will be relatively free from color impurities.

Where the purest product is desired, the soap stock resulting from a preliminarily degummed oil, and which is free from color impurities may be employed as the saponifying agent in the present process. However, at the high temperatures contemplated in the preferred process of the present invention, many of the impurities above referred to are broken down into volatile compounds, which may be removed from the soap by vaporization, thus permitting a relatively high grade soap to be produced even when a soap stock containing relatively large amounts of impurities is employed. Thus by the employment of my dehydration and deodorization process as described in my copending application Serial No. 318,753, filed February 13, 1940, now Patent No. 2,230,196 granted January 28, 1941, of which this case is a continuation-in-part, it is possible to produce a relatively pure soap when using a relatively impure soap stock as the saponifying agent.

It is therefore the primary object of the present invention to provide a process for the production of soap utilizing as the saponifying agent the alkali-soap stock mixture resulting from the alkali refining of a glyceride oil.

It is another object of the present invention to provide a process utilizing the alkali-soap stock mixture resulting from the refining of a preliminarily degummed oil as a saponifying agent.

It is a further object of the present invention to employ in a soap making process a waste alkali solution resulting from the alkali refining of a glyceride oil.

These and other objects will be apparent from the following description of the process and the drawing in which:

Figure 1 is a diagrammatic sketch of an apparatus suitable for carrying out the process of the present invention; and

Figure 2 is a diagrammatic fragmentary sketch of an apparatus which may be employed to carry out a modified process:

Referring more particularly to Figure 1, 10 indicates a tank as a source of supply for the oil to be refined. The tank 10 may be provided with a heating coil 11 to bring the oil to a predetermined temperature at which the oil is flowable. A tank 12 may contain neutralizing agent and may be provided with a heating coil 13 to heat the neutralizing agent to a desired temperature for mixing with the oil. A stream of oil may be withdrawn from the tank 10 by a pump 14 and delivered through a heat exchange device 15 to a flow mixing device 16. The heat exchange device 15 preferably includes a coil 17 through which the oil is passed, which coil is positioned in a casing 18 through which any desired heating medium may be circulated. Neutralizing agent may be withdrawn from the tank 12 by a pump 19 and delivered to the flow mixer 16. The pumps 14 and 19 are preferably arranged to deliver accurately proportioned streams of oil and neutralizing agent respectively to the mixer 16, and one way of accomplishing this is to drive the pumps 14 and 19 from a variable speed electric motor 20 with a variable speed device 21 positioned between the motor and the pump 19. The flow mixing device may be of any suitable type capable of repeatedly forming a thorough mixture of oil and reagent. The mixing device disclosed in Patent No. 2,142,062 is preferred, but another device such as a closed mechanical agitator or a colloid mill may be employed if desired.

The oil and reagent are preferably mixed under pressure and out of contact with the atmosphere. The resulting mixture may be passed through a heat exchange device 22 similar to heat exchange device 15 and delivered to the continuous centrifugal separator 23.

The refined oil is withdrawn at 24 while the soap stock is discharged at 25 into a mixing tank 26. Saponifiable matter such as free fatty acids, glycerides, and the like, may be preheated by coil 27 located in supply tank 28 and from there discharged into the mixing tank 26 through conduit 29. Mixing tank 26 may be provided with an agitator 30 driven by motor 31. The saponifiable matter and the soap stock containing the excess alkali may be intimately mixed in the tank 26. Preferably the agitation is continuous so that a mixture of uniform composition may be continuously withdrawn from the bottom of tank 26. The tank 26 may be closed from the atmosphere where conditions, such as the temperature of the saponifiable matter or soap stock, make contact with the atmosphere undesirable.

Pump 32 may be employed to withdraw a stream of the mixture from tank 26 through con-

duit 33 and force the same under pressure into heating coil 34 located within heating chamber 35. A suitable burner 36 may be employed utilizing gas or other combustible material as the heating medium. The mixture of soap stock, alkali and saponifiable matter is heated during passage through the coil 34 and the reaction may be substantially completed within the coil. It is preferred to supply sufficient additional heat to the mixture in the coil or coils so that when the reacted mixture is discharged from the coil into a lower pressure chamber the heat within the mixture will be sufficient to effect vaporization of the contained impurities. The reacted mixture is withdrawn from the coil through conduit 37 and is preferably discharged into a vaporizing chamber 38 similar to that disclosed in my prior Patent 2,218,279. This vaporizing chamber is composed of an inner chamber 39 around which is disposed the outer jacket 40. The space 41 between the inner and outer jackets may be employed to regulate the temperature of the inner chamber by means of a suitable heat exchange medium. Suitable inlet and outlet passages 42 and 43 may be employed for this purpose. Steam may be introduced into the chamber if desired, through the conduit 44. The chamber terminates at the bottom in a conical shaped member which is adapted to discharge the contents of the chamber into a screw conveyor 45, by means of which the contents of the chamber may be discharged to atmosphere without permitting atmospheric gases to enter the chamber. The screw conveyor 45 is preferably jacketed as at 46 so that a cooling medium may be circulated around the screw conveyor thus enabling the soap mixture being discharged from the chamber to be reduced in temperature so that it will form a vacuum seal for the chamber and not be deleteriously affected by contact with the atmosphere. The mixture in conduit 37 may be discharged into the chamber by means of nozzles 47 which direct the sprayed material down along the inner walls of the chamber. While it is preferred to complete saponification in coil 34, saponification may be completed in tank 26 by means of the latent heat of the reactants or by means of additional heat supplied therein. Likewise, a separate saponification coil such as employed in my Patent No. 2,178,927 may be used. In these cases, coil 34 may be employed primarily to supply heat for the vaporization of impurities.

Upon introduction to the vaporizing chamber the pressure on the saponified mixture may be reduced. The latent heat within the mixture may be sufficient to vaporize glycerine, if a glyceride oil was employed, water and other impurities. These vapors may be withdrawn through conduit 48 and passed into a suitable vapor separating chamber 49. Any unvaporized material may be returned to the vaporizing chamber by means of conduit 50. The vapors from the vapor separating chamber may be passed through suitable fractional condensers 51, 52 and 53 where individual constituents, such as glycerine, water, and other impurities may be separated from one another if desired. Pump 54 may be employed to maintain the chamber and the condenser systems under vacuum.

In the preferred process sufficient soda ash solution of proper concentration to provide effective separation is admixed in flow with the oil in a single mixing operation in accordance with Figure 1. The concentration of the aqueous so-

lution of soda ash will vary with different oils but will usually range between 12° and 20° Bé., although with certain oils it may be possible to employ concentrations as low as 5° Bé., and with other oils as high as 30° Bé. In accordance with my Patent 2,190,594, an extremely large excess of soda ash may be employed, such as from three to twelve times the amount necessary to neutralize the free fatty acids. The soap stock mixture discharged at 25 contains this large excess of soda ash. When free fatty acids are employed as the saponifiable material the soda ash reacts very readily with the free fatty acids to produce soap. In this event relatively little heat is required in coil 34 to effect the reaction, but it is preferred to heat the mixture under pressure to a fairly high temperature in order to produce a fluid mixture and so that the resulting mixture will contain sufficient heat to vaporize the impurities therein when the mixture is discharged into the lower pressure chamber for vaporizing. Thus temperatures in the coil will range from approximately 250° F. to 600° F. depending upon the nature of the soap stock, saponifiable material, and quality of soap desired. It is possible, however, to add additional heat to the sprayed material in the vaporizing chamber by means of the heat exchange jacket surrounding the same and by means of the pipe through which superheated steam may be introduced.

Where glyceride oil is the saponifiable material employed higher temperatures are usually desirable to expedite the saponification of the neutral oil. Accordingly higher temperatures and higher pressures may be employed within coil 34.

In some cases it is desirable to add to the soap stock in tank 26 more saponifiable material than the excess alkali in the soap stock will saponify. In this case additional alkali preferably in the form of a caustic soda solution may be introduced into the mixture. This is particularly desirable where the soda ash solution employed in refining was of a high concentration, thus resulting in a very viscous soap stock. The water contained in the caustic soda solution added to the mixture serves to dilute the mixture and make it more easily flowable. Where desired it is apparent that excess water may be introduced in order to make the mixture sufficiently flowable. The caustic soda added also is of value when glyceride oils are employed as the saponifiable material, or when the soap stock contains substantial quantities of entrapped glyceride oil, since the caustic soda is more effective in saponifying the neutral glyceride oil than is the soda ash. The soda ash employed as the saponifying agent may release carbon dioxide upon neutralization of the free fatty acid or upon saponification of the glyceride oils. This carbon dioxide evolved within the coil 34 is of advantage in effecting vaporization of the undesirable constituents upon discharge of the mixture into the vaporizing chamber. In addition this carbon dioxide insures that any gas present within the vaporizing chamber will be relatively inert with respect to the soap so that deleterious effects of oxygen upon soap within the vaporizing chamber may be obviated.

In Figure 2 I have illustrated a modification of the present process in which the soap stock from the refining operation and the saponifiable matter are mixed in stream flow rather than being mixed within a tank as in Figure 1. Figure 2 merely shows the deviation of this process from that of Figure 1. Accordingly, the similar portions have been omitted and only the variation

has been illustrated. The refining process up to the centrifugal separation may be the same as in Figure 1. Likewise the reaction of the mixture in the coil and the recovery of the soap from the reaction mixture may be the same as in Figure 1. The soap stock discharged from the centrifuge at 25 is run into tank 26. This tank is preferably supplied with a heating coil 60 so that the soap stock may be heated up to such a condition that it can be pumped. This tank likewise contains an agitator 31 which aids in keeping the soap stock in a flowable condition. The saponifiable matter is contained within a tank 61 which is supplied with a heating coil 62, by means of which the saponifiable matter is preferably preheated. Streams of soap stock and saponifiable matter are withdrawn by means of pumps 63 and 64 respectively. These pumps may be driven by means of a variable speed motor 65. A variable speed drive 66 may be interposed between the two pumps so that the proper proportion of soap stock and fatty matter may be withdrawn from the receptive tanks. These streams of soap stock and saponifiable matter may be mixed within the mixer 67 and from it may be passed into the heating coil 34 within the chamber 35, as was the case in Figure 1. In this manner it is possible to mix the reactants in stream flow as distinguished from maintaining a supply of the mixed reactants in a tank as in Figure 1.

It is preferred to preheat the saponifiable material to a degree at which substantial saponification will take place immediately upon contact with the saponifying reagent. When fatty acids are the saponifiable material employed, it is preferred to preheat them to such a temperature that they will not ball up upon contact with the saponifying reagent. Thus if the fatty acids are preheated to such a temperature that the resultant soap is molten no difficulty from balling up is encountered.

In accordance with my prior patent referred to herein, other non-saponifying alkalies such as alkali-salts of alkali metals, for example, tri-sodium phosphate, disodium phosphate, sodium silicate, and equivalent potassium salts; alkali-salts of alkaline earth metals; and amines such as ammonia, triethanolamine, etc., may in some instances be substituted in part or all for the soda ash. That is, other non-saponifying neutralizing agents may be employed alone or in various admixtures, as well as in admixture with soda ash. Soap stock resulting from the employment of various of these non-saponifying neutralizing agents may be employed in the present process. However, in view of the difficulty with which esterified fatty acids such as glycerides and the like are saponified, higher temperatures and pressures may be required in order to effect saponification. In these cases it may be advisable to employ more saponifiable material than is required to react with the excess alkali in the soap stock. In this event it is preferred to add sufficient caustic soda or potash to react with the excess saponifiable matter. In this way, as was pointed out previously, the caustic alkali aids in the saponification of the esterified fatty acids. When free fatty acids are employed as the additional saponifiable matter, relatively little difficulty is encountered in effecting the reaction.

In the event the amines are used as the neutralizing or saponifying agent, it is preferred to omit the vacuum dehydration step as there is a tendency for the amine soaps to decompose into

the fatty acid and amine, the latter vaporizing at the low pressure in the vacuum chamber.

The various modifications of the process of the present invention are applicable to vegetable and animal oils in general. Such vegetable oils as cottonseed oil, corn oil, soya bean oil, linseed oil, sesame oil, etc., are within the contemplation of the invention. The term "animal oils" is also intended to include fish oils such as sardine, menhaden, or herring oils. By the employment of the term "saponifiable matter" in the claims I intend to include free fatty acids, glyceride oils, as well as other esters of fatty acids either with mono-hydric or with poly-hydric alcohols. By the employment of the term "oils" or "oil" in the claims it is intended to include glyceride fats or oils, irrespective of the viscosity thereof.

While I have disclosed the preferred embodiments of my invention, it is understood that the details thereof may be varied within the scope of the following claims.

What I claim is:

1. The process of purifying soap stock containing excess alkali from the alkali refining of glyceride oils and making soap therefrom, which comprises, adding saponifiable material to said soap stock to react with said excess alkali, heating the resulting mixture to a temperature sufficiently high to break down odoriferous substances contained therein and removing vaporizable materials from said soap stock in vapor form to produce an improved soap from said soap stock.

2. The process of purifying soap stock containing water, excess alkali and odoriferous substances from the alkali refining of glyceride oils and making soap therefrom, which comprises, adding sufficient saponifiable material to said soap stock to react with said excess alkali, heating the resulting mixture to a temperature sufficiently high to break down said odoriferous substances and vaporizing water and other vaporizable materials from said soap.

3. The process of purifying soap stock containing excess alkali from the alkali refining of glyceride oils and making soap therefrom, which comprises, adding sufficient saponifiable material to said soap stock to react with said excess alkali, continuously heating a stream of the resulting mixture to a temperature sufficiently high to break down odoriferous substances contained therein, discharging the resulting heated stream into a vapor separating chamber and removing

vaporizable materials from the resultant soap in said chamber.

4. The process of purifying soap stock containing excess alkali from the alkali refining of glyceride oils and making soap therefrom, which comprises, adding sufficient saponifiable material to said soap stock to react with said excess alkali, heating a flowing stream of said mixture under pressure and out of contact with the atmosphere to a temperature sufficiently high to break down odoriferous substances contained therein, discharging the resulting heated stream into a vapor separating chamber and withdrawing vaporizable materials in vapor form from said chamber at a rate sufficient to maintain a vacuum therein.

5. The process of purifying soap stock containing excess alkali from the alkali refining of glyceride oils and making soap therefrom, which comprises, adding saponifiable material to said soap stock to react with said excess alkali, heating a flowing stream of the resulting mixture under pressure and out of contact with the atmosphere to a temperature sufficiently high to break down odoriferous substances contained therein, discharging the resulting heated stream to a vapor separating chamber, withdrawing vaporizable materials from said chamber at a rate sufficient to maintain a vacuum therein, and continuously removing soap in molten anhydrous form from said chamber.

6. The process of purifying soap stock containing excess alkali from the alkali refining of glyceride oils and making soap therefrom, which comprises, adding saponifiable material to said soap stock to react with said excess alkali, heating the resulting mixture during continuous movement thereof to a temperature sufficiently high to break down odoriferous substances contained therein, and removing vaporizable materials from said soap stock as vapors to produce an improved soap.

7. The process of purifying soap stock containing excess alkali from the alkali refining of glyceride oils and making soap therefrom, which comprises, adding saponifiable material to said soap stock to react with said excess alkali, heating the resulting mixture to a temperature from 250 to 600° F. and sufficiently high to break down odoriferous substances contained therein and removing vaporizable materials from said soap stock in vapor form to produce an improved soap.

BENJAMIN CLAYTON.
